[57] CLAIM

The ornamental design for a table, as shown and described.

DESCRIPTION

FIG. 1 is a perspective view of a table, showing my new design;

FIG. 2 is a top view of the table of FIG. 1.

FIG. 3 is a front view of the table of FIG. 1. The rear view and the left and right side views are visually identical to the view shown in FIG. 3.

FIG. 4 is a bottom view of the table of FIG. 1; and, FIG. 5 is a detail view to show the exterior contour of the rim of the table top.

FIG. 1

FIG.2
